No. 65,867.

PATENTED JUNE 18, 1867.

E. M. BATES.
CORN HUSKER.

United States Patent Office.

EDWARD M. BATES, OF EAST ROCHESTER, OHIO.

Letters Patent No. 65,867, dated June 18, 1867.

CORN-HUSKER.

The Schedule referred to in these Letters Patent and making part of the same.

TO ALL WHOM IT MAY CONCERN:

Be it known that I, EDWARD M. BATES, of East Rochester, in the county of Columbiana, and State of Ohio, have invented certain new and useful improvements in Corn-Huskers; and I do hereby declare that the following is a full and complete description of the construction of the same, reference being had to the accompanying drawings making a part of this specification, in which—

Figure 1 is a side view of the husker.

Figure 2 is a top view.

Figure 3 is also a side view.

Like letters of reference refer to like parts in the views.

This implement consists of a metallic rod, curved and shaped as shown in fig. 1, in which it will be seen that the tail end of the creature is curved into a loop or ring, A, and that the middle section B is bent into the shape of an inverted U, so also is the section C bent in the same shape, but reversely. D, the head of the reptile, is somewhat flattened out, and terminates in an abrupt or rounded point, E.

The manner of using his snakeship is as follows: The third finger of the right hand is inserted in the ring or loop A; this will bring the curve B over the second finger, and the curve C under the first, thus bringing the head or point E in opposition to the thumb. The husker is then used in the same manner as an ordinary husking-pin, viz, by taking the unhusked ear in the left hand, and then with the point of the implement tear the husk so that it can be stripped from the ear.

This husker is extremely neat and convenient, and will not slip from the hand, nor bite while using, and, being supported by the finger, does not require to be grasped tightly by the hand, or tied to the same, as the pin in ordinary use.

What I claim as my improvement, and desire to secure by Letters Patent, is—

A curved or scrolled corn-husker, constructed in the manner as and for the purpose described.

EDWARD M. BATES.
